REINFORCING FABRIC SUPPORT

Filed Dec. 6, 1926

UNITED STATES PATENT OFFICE

WILLIAM E. WHITE, OF CHICAGO, ILLINOIS, ASSIGNOR TO KALMAN STEEL COMPANY,
OF CHICAGO, ILLINOIS, A CORPORATION OF DELAWARE

REINFORCING FABRIC SUPPORT

Application filed December 6, 1926. Serial No. 152,892.

My invention relates to concrete slab reinforcement and particularly to a device intended to support or vertically space a fabric preliminary to the pouring of the concrete.

An object of the invention is to provide a device of the utmost simplicity, that may be quickly applied without the use of tools, and that will possess the utmost rigidity relative to the weight of metal employed. The device comprises essentially a support or stand, preferably having a broad base, and a seat at its upper end. With this device is associated a pair of spring wire arms, adapted to surround a crossed bar or rod, and to hook over the bar carried in the seat in the support. While the device is described as particularly intended for use in supporting fabric in which the transverse and longitudinal rods are rigidly joined as by welding, it will function equally well for supporting, spacing and joining crossed bars that are not united.

I realize that the main result sought by the use of the device here disclosed has been attempted, in part at least, by devices heretofore suggested, and my improvement resides in the details of construction and arrangement by means of which my device may be economically constructed and quickly installed.

The invention will be more readily understood by reference to the accompanying drawings, in which:

Fig. 1 is a side view of the device of my invention as installed;

Fig. 2 is a view taken at right angles to that of Fig. 1;

Fig. 3 is a view similar to Fig. 2, taken from the opposite direction, and;

Fig. 4 is a plan view thereof.

In the drawings, it will be seen that the supporting and spacing element consists of a sheet metal section having side flanges, 10, and a central rib, 11. The section is originally straight, as indicated in dotted lines in Fig. 1. In a preliminary operation, the rib is provided with a V-shaped notch indicated at 12 in Fig. 1, and a similar notch indicated at 13. Thereafter the lower portion, 14 is bent up into the full line position, with the

diagonal lines of the notch in contact, thus providing a broad flat base. In a subsequent operation, the upper portion 15 is bent into the full line position of Fig. 1. As a result of the notching in the semi-circular rib, 55 an aperture of generally oval shape is produced, as indicated in Fig. 1. Thus when the portion 15 is bent backward into the position of Fig. 1, a double seat is provided for the bar A; that is, the bar will have 60 contact with the support at the points, 17 and 18.

In order to engage and hold the bar B, I provide the spring arms, 19, 20, having hooked ends, 21, 22, and a connecting member, 23, the connecting member being held at the bend of the flanges at the junction of the part, 15, with the main support. Preferably also, the connecting member, 23, is bent downward as at 16, to underlie the bar 70 A, as best shown in Fig. 3, thus providing an additional support for the bar A at a point between the points, 17, 18.

The arms, 19, 20, are constructed to originally lie in the position indicated by the dotted lines in Fig. 1 thus facilitating the engagement of the device with the crossed rods. After engagement the arms are swung into the full line position and the hooked ends are caused to engage opposite sides of the 80 bar A.

The support may be very economically produced, and the wire arms are of simple automatic machine manufacture. The assembly is likewise a simple operation.

Obviously certain modifications may be made in the construction shown, and I do not wish to be limited except as indicated in the appended claims.

I claim:

1. In combination, a sheet metal support having a longitudinal rib, a lateral foot and a seat for a bar at its upper end, a pair of connected spring arms, the connection between the arms being held by ears on the support, said arms being adapted to pass over and under a crossed bar and be sprung into engagement with a bar held in said seat.
2. In combination, a sheet metal support having a rib and side flanges, the rib being 100

cut out near the upper end of the support to provide a seat, the flanges constituting ears, and a pair of connecting spring arms, the connecting member being held by the ears on the support, said arms being adapted to be wrapped around a crossed bar and to engage with the bar held in said seat.

3. In combination, a sheet metal stand having a central longitudinal rib, the rib near the upper end of the stand having a triangular notch, the terminal above the notch being bent backwardly and downwardly to provide a recess and laterally spaced supports for a bar, and a spring arm having a portion held by the bent-over portion of the sheet metal, said spring arm acting to engage and hold crossed bars.

4. A vertical spacer and support for crossed bars, which consists of a rigid ribbed sheet metal support having a pair of bar seats for the same bar at its upper end, a right-angularly disposed, channel shaped base portion, and spring means on said support for engaging and holding a pair of crossed bars.

5. A vertical spacer and bar support, comprising, in combination a rigid metal support, said support having a reenforcing rib therein, a pair of side by side seats for the same bar, a right-angularly disposed, channel shaped foot at the base of said support, and spring means on said support for engaging and holding a pair of crossed bars.

6. A vertical spacer and bar support comprising a channel shaped support, a right-angularly disposed, channel shaped foot on said support, a pair of bar seats for a single bar formed out of the metal at the upper end of said support and spring means on said support for engaging and holding a pair of crossed bars.

In testimony whereof I have affixed my signature.

WILLIAM E. WHITE.
